PULSE STARTING SYSTEM FOR FLUORESCENT LAMPS

John H. Campbell, Painesville, Ohio, assignor to General Electric Company, a corporation of New York

Application March 14, 1950, Serial No. 149,535

2 Claims. (Cl. 315—97)

This invention relates generally to the starting of gaseous electric discharge devices such as fluorescent lamps, and more particularly to a system of pulse starting which is most effective and economical in large installations of fluorescent lamps.

In the present state of development in fluorescent lamps, a considerable quantity of equipment is required for the sole purpose of starting the arc or discharge within the lamp, and this equipment is completely inoperative during normal lamp operation. In many installations not only is the starting equipment not gainfully utilized during operation, but it actually causes a wastage of electrical energy.

Accordingly, it is an object of my invention to provide a new and improved system of starting and operating fluorescent lamps which possesses inherent features of economy by providing only one starting device for a number of lamps in multiple.

A further object of my invention is to provide a new and improved system of starting and operating fluorescent lamps which eliminates the need for high voltage transformers when used with instant start lamps.

Still a further object of my invention is to provide such a system which eliminates the need for thermal or glow switches when operated with preheat of the electrodes in a fluorescent lamp.

A feature of my invention, as applied to an installation of fluorescent lamps in multiple, is the provision of a central source for generating high intensity pulses of short time duration, which are either substituted for the line voltage or superimposed thereon for a brief interval at starting only. During normal operation, the central source of pulsed voltage is effectively disconnected from the line.

For further objects and advantages and for a better understanding of my invention, attention is now directed to the following description and accompanying drawings. The features of my invention believed to be novel will be more particularly pointed out in the appended claims.

Referring to the drawings:

Fig. 1 is a block diagram illustrating in generalized form a pulse starting and operating system for fluorescent lamps in accordance with my invention.

Fig. 2 is a schematic diagram of a preferred embodiment of my invention illustrating a pulse starting system for fluorescent lamps operated in pairs with the well-known lag-head two-lamp circuit.

Fig. 3 shows a pair of curves illustrating the waveform of the line voltage and of the pulse voltage generated in the preferred embodiment of Fig. 2.

Fig. 4 is a schematic diagram illustrating another embodiment of my invention which is particularly adapted to the operation of low wattage fluorescent lamps of the preheat type in multiple.

Fig. 5 illustrates another embodiment of my invention which is particularly adapted to the operation of fluorescent lamps from a direct current supply.

Referring to Fig. 1, the block diagram therein illus-

2

trates the general application of my pulse starting system to a number of fluorescent lamps in parallel. The various components of the blocks will be described in detail with reference to the succeeding figures. In general, my invention finds its most advantageous application where a number of fluorescent lamps, as represented by blocks 1, 2, and 3, are to be operated in parallel from a common supply line 4, 5, and are to be controlled from a central point. Then, instead of providing starting equipment for each fluorescent lamp operating circuit, I provide a single source of voltage pulses at the central switching point, said source being represented by block 6. The pulse source may either substitute a series of short high voltage pulses for the regular supply voltage during a brief period immediately after a manual control switch is first turned on; or, again, it may superimpose high voltage pulses on the regular line voltage waveform. The former is preferably used with fluorescent lamps of the instant start type, and the latter with fluorescent lamps requiring preheat of the cathodes. With instant start lamps, the pulse energy must be high enough to cause a hot spot to form on the cathodes of all the lamps, but not so high as to cause any one of the lamps to strike its normal arc discharge because such lamp would then absorb all the energy transmitted from the pulse source and prevent the other lamps in multiple from starting. With fluorescent lamps of the type requiring preheat of the cathodes, the pulse energy provided need be just sufficient to ionize the gas in the lamps without striking the arc discharge.

Referring to Fig. 2, I have illustrated therein a preferred embodiment of a pulse source operated in conjunction with a lag-lead two-lamp circuit and I have enclosed the constituent elements within blocks in dotted outline, these blocks being denoted by like reference numerals as in Fig. 1. The pulse source comprises a saturable choke coil or inductor 7, the primary winding 8 of a transformer 9, and a capacitor 11 connected in series with a switch 12 across the supply 4, 5. Transformer 9 is provided with a secondary winding 10, one side of which is connected directly to the utilization line 4' and the other side of which may be connected to the utilization line 5' through switch 12. The supply line 4 may be connected to the utilization line 4' by means of a switch 12', whereas the supply line 5 continues directly into the utilization line 5'.

The utilization lines 4', 5', lead directly to the two input terminals of the operating circuit of a pair of fluorescent lamps 13, 14 of the low pressure positive column type. The particular operating circuit illustrated consists of a step-up autotransformer 15 comprising a portion 16 across which the utilization lines 4', 5' are connected, the junctures with these lines being in effect the input terminals. The high voltage side of autotransformer 15 is connected through an inductor 17 to lamp 13 and through an inductor 18 in series with a capacitor 19 to lamp 14. In accordance with well-known principles, inductor 17 causes lamp 13 to operate with a lagging power factor, whereas the combination of inductor 18 and capacitor 19 causes lamp 14 to operate with a leading power factor. The operating circuit for lamps 13 and 14 may be of the type commonly utilized for the switch starting of 40 watt lamps, and which is commonly known in the fluorescent lamp industry as a lag-lead two-lamp switch-start ballast. In the present instance, I utilize the circuit without the switch starting connections, and I preferably provide lamps 13 and 14 with cathodes capable of withstanding instant starting. For instance, lamps 13 and 14 may be 40-watt instant start fluorescent lamps which are provided with cathodes containing large amounts of emissive material. It might be mentioned at this point that conventional operation of instant start

lamps in accordance with the prior art, requires a transformer having an open circuit to operating voltage ratio of approximately 4 to 1, whereas transformer 15 mentioned herein provides an open circuit to operating voltage ratio of approximately 2 to 1. Accordingly, transformer 15 could not start lamps 13 and 14 without the additional equipment contained in pulse source 6 whose operation will now be described.

To put lamps 13 and 14 into operation and, likewise, other lamps which may be connected in similar fashion as represented symbolically by blocks 2 and 3, switch 12 is initially closed for a few seconds, the exact length of time depending on various factors which will be considered hereafter, and switch 12' is then closed simultaneously with the reopening of switch 12. It need hardly be mentioned that switches 12 and 12' may be mechanically interlocked by means of a delayed escape mechanism such that the operation of a single lever will perform the three operations just mentioned in their proper sequence. Since such switching mechanisms are well known and available on the market, none has been illustrated in the drawings.

When switch 12 is initially closed, the current flows through the branch circuit comprising reactor 7, primary winding 8 and capacitor 11 in series. These elements are so designed that the magnetic core of reactor 7 saturates due to the current through the circuit. As a result, the voltage induced in secondary winding 10 is characterized by a high intensity peak of short time duration. Referring to Fig. 3, curve 20 therein illustrates the sinusoidal waveform of the supply voltage received from the line conductors 4, 5 and curve 21 illustrates the sharply peaked waveform of the pulses impressed on the utilization circuit 4', 5'. It will be observed that the pulse voltage impressed on the utilization circuit, whereas it attains a high peak, actually contains less energy than the sinusoidal line voltage due to the short time duration of the pulses. Transformer 9 has a step-up ratio providing a peak voltage having a maximum amplitude approximately twice the amplitude of the line voltage.

The pulses are impressed through the utilization circuit 4', 5' on the autotransformer 15 of the lamp operating circuit contained in block 1, and similarly on the autotransformers contained in the other blocks 2 and 3. Autotransformer 15 causes the pulse voltage applied to it to be increased or stepped up substantially in accordance with its turn ratio. Thus, since transformer 9 provides a peak voltage of twice the amplitude of the supply voltage, and since autotransformer 15 provides its usual 2 to 1 voltage step up, the peak voltage applied to lamps 13 and 14 is approximately four times the line voltage. The energy content of the pulses, which energy content is dependent upon their duration, is sufficient to cause the lamps to form a hot spot on their cathodes but is not sufficient to cause the normal arc discharge to occur within the lamps due to the spacing of consecutive pulses. It is important that this requirement be met, because I have found that if the energy content of the pulse waveform is too high, one of the lamps will arc and will absorb the energy which would otherwise have gone to produce hot spots in the remaining lamps, so that these will not start.

With regard to the requirement that all the lamps form a hot spot and that none attain a normal arc discharge, I have found that this may be achieved successfully by providing pulses of suitably short time duration with respect to their spacing or repetition interval. It is a well-known fact that an arc discharge through a gas has a negative resistance characteristic. However, if sharp pulses of voltage at comparatively long time intervals apart are utilized, rather than a unidirectional voltage or a sinusoidal alternating voltage, the degree of ionization of the gas cannot increase at the same rate as the steep waveform of the pulse; and, as a result, the discharge exhibits a positive resistance characteristic, that is, one in which the voltage

drop increases rather than decreases with current. Accordingly, to insure that all the lamps form a hot spot, I provide the pulses with a short time duration with respect to their spacing or repetition interval; and, to take care of a greater number of lamps, I preferably increase this peak pulse amplitude, rather than their time duration.

The pulse circuit may readily be designed such that all the lamps in the operating circuits form hot spots on their cathodes within a few seconds after the initial closing of switch 12. Thereafter, the closing of switch 12' applies the normal sinusoidal line voltage directly across autotransformer 15; and since this voltage has a sufficient energy content to support an arc discharge in all the lamps, normal operation ensues practically immediately.

Referring to Fig. 4, I have illustrated therein another embodiment of my invention which is particularly adapted to the starting of fluorescent lamps whose cathodes require preheat at starting in order to insure reasonable life. The pulsing circuit contained within block 6 is quite similar to that illustrated in Fig. 2 with this variation that the secondary winding 10 of transformer 9 is arranged to be placed in series between the supply line 4 and the utilization line 4'. Switch 12', in this particular embodiment, is arranged to short circuit secondary winding 10 and provide a direct connection between lines 4 and 4' when closed.

The operating circuit contained in block 1 comprises a fluorescent lamp 30 of the type having a pair of thermionic electrodes 31 and 32 which normally require the application of heating current in order to raise them to an electron emitting temperature and prevent destructive sputtering of activated electron emissive material at starting. Lamp 30 is connected in series with a current limiting reactor 33 across the utilization lines 4', 5'. This circuit comprises, in addition, an electrode heating transformer 34 of which the primary winding 35 is connected in parallel with lamp 30, and of which the secondary windings 36 and 37 are connected across thermionic electrodes 31 and 32, respectively.

The operation of the switches in the embodiment of Fig. 4 is similar to that described with reference to Fig. 2, the only difference being that the pulse voltage is added to the sinusoidal voltage provided by the supply. Thus, the utilization lines 4', 5' receive a composite voltage containing both the normal supply voltage and the pulse voltage. The pulses cause the gaseous column within lamp 30 to ionize. In addition, the supply voltage operates in normal manner on transformer 34 whose secondary current heats electrodes 31 and 32. When the electrodes have attained their electron emitting temperature, since the gaseous column has already been ionized by the pulses, the arc strikes without difficulty. One of the advantages of supplying pulses in this circuit is that the lamps ionize due to the high intensity peaks of the pulses and thereafter cannot fail to start on the normal line voltage. Thus, there is no necessity for thermal or glow switches to provide an inductive surge to initiate ionization within the lamps.

Referring to Fig. 5, the pulsing circuit 6 therein illustrated is designed for pulse starting lamps from a direct current supply, in accordance with my invention. The pulse generator proper comprises a tapped inductor 40 connected, in series with a discharge tube 41 and switch 12, across the unidirectional supply 4, 5, the tapped portion of the inductor being shunted by a capacitor 42. Inductances 43 and 44 and shunt capacitor 45 constitute a T-filter, which is provided in order to prevent pulse energy from feeding back to the direct current supply. The lamp operating circuit comprises lamps 13 and 14 connected in series with resistive ballasts 46 and 47 across the utilization lines 4', 5'. Ballasts 46 and 47 may be the usual tungsten filament lamp.

In operation, when switch 11 is initially closed, a series of discharges occur across the electrodes of tube 11 which

produce trains of damped oscillations in capacitor 42 and inductor 40. The T-filter forces these trains of oscillations to travel through the utilization lines 4', 5' to the lamp operating circuits whereupon hot spots are formed on the lamp electrodes. After the arcs have struck within the lamps, switch 11 is opened and the generation of pulses ceases, the lamps thereafter operating in normal fashion with ballasting provided by the tungsten lamps 46 and 47.

While my invention is applicable to the operation of a single lamp, it naturally finds its most advantageous applications in combination with a number of lamp circuits connected in multiple. Thus, it is ideal for the operation of large numbers of lamps in buildings or halls wherein it is desirable to have a single control switch for all the lamps. It will be evident to those skilled in the art that it is economically advantageous to provide a single pulsing source and thereafter provide transformers having low step-up ratios, such as step-up ratios of 2 to 1, for each individual lamp, than to provide at each individual lamp a transformer having a high step-up ratio, for instance 4 to 1, as would be required in the absence of a pulse circuit. My invention provides economic advantages not only from the point of view of first installation cost, but also from the point of view of electrical consumption, as the operating losses in transformers having an open to operating voltage ratio of 2 to 1 may always be made lower, other factors being equal, than in transformers having a ratio of 4 to 1.

Although certain specific embodiments have been shown and described, it will, of course, be understood that various modifications may be made without departing from the invention. Thus, the particular pulsing circuits which I have illustrated may be replaced by other circuits known to the art which perform similarly. Likewise, the lamp operating circuits which I have illustrated are intended as nonlimitative examples, and it will be apparent that various other ballasting circuits commonly utilized with fluorescent lamps may be substituted therefor. The appended claims are, accordingly, intended to cover any such modifications coming within the true spirit and scope of the invention.

What I claim as new and desire to secure by Letters Patent of the United States is:

1. A starting and operating system for fluorescent lamps of the thermionic cathode positive column type, comprising a plurality of said lamps, an alternating voltage supply, operating circuits for said lamps each comprising a pair of input terminals and connected in parallel across said supply, each of said operating circuits comprising a high leakage reactance transforming means having a normal open circuit to operating voltage ratio less than that required to start said lamps but sufficient to provide regulation after starting, and a pulsing circuit connected between said operating circuits and said supply, 55

5 said pulsing circuit comprising a saturable reactor, the primary winding of a transformer and a capacitor serially connected through a first switch across said supply, and a secondary winding of said transformer with a second switch and connections for temporarily substituting said secondary winding for said alternating supply to energize said operating circuits, said saturable reactor and said capacitor being proportioned to produce pulses of short time duration and high intensity in said secondary winding when said first switch is closed, said pulses having a time duration short enough to cause said lamps to exhibit a positive resistance characteristic thereto.

2. A starting and operating system for fluorescent lamps of the positive column type having filamentary thermionic cathodes, comprising a plurality of said lamps, an alternating voltage supply, operating circuits for said lamps each comprising a pair of input terminals and connected in parallel across said supply, each of said operating circuits comprising reactive transforming means having a normal open circuit to operating voltage ratio less than that required to start said lamps but sufficient to provide regulation after starting and including means for supplying preheating current to said electrodes, and a pulsing circuit connected between said operating circuits and said supply, said pulsing circuit comprising a saturable reactor, the primary winding of a transformer and a capacitor serially connected through a first switch across said supply, and a secondary winding of said transformer with a second switch and connections for temporarily substituting said secondary winding for said alternating supply to energize said operating circuits, said saturable reactor and said capacitor being proportioned to produce pulses of short time duration and high intensity in said secondary winding when said first switch is closed, said pulses having a time duration short enough to cause said lamps to exhibit a positive resistance characteristic thereto.
